Patented Jan. 3, 1922.

UNITED STATES PATENT OFFICE.

CHARLES A. TURNER, OF CHICAGO, ILLINOIS, ASSIGNOR OF ONE-HALF TO FRED G. WALDENFELS, OF CHICAGO, ILLINOIS.

SYSTEM OF ELECTRIC-CURRENT DISTRIBUTION.

1,402,386.

Specification of Letters Patent.

Patented Jan. 3, 1922.

Application filed February 16, 1920. Serial No. 359,171.

To all whom it may concern:

Be it known that I, CHARLES A. TURNER, citizen of the United States, residing at Chicago, in the county of Cook and State 5 of Illinois, have invented a certain new and useful Improvement in Systems of Electric-Current Distribution, of which the following is a full, clear, concise, and exact description.

10 My invention relates to systems of electric current distribution and resides in the provision of improved means for supplying current to translating devices at low voltage from circuits furnishing current to 15 other translating devices at high voltage. The system of my invention, for example, enables the operation of house bells by current supplied from commercial house lighting circuits.

20 The system embracing my invention is inclusive of an electro-magnet, having an armature switch, and a high resistance element included in series with this magnet in bridge of the mains; a second electro- 25 magnet, also having an armature switch, and a translating device in series with this second magnet and together therewith in parallel with the first magnet, a normally open switch for including the second magnet and the translating device in circuit, a shunting resistance element brought in parallel with the translating device and in shunt of the first magnet by the armature switch of the second magnet upon the attraction thereof, and a normally open shunt 30 about said high resistance element and established by the armature switch of the first magnet upon the release thereof, there being a current reducing winding in the 35 connection between one terminal of the shunting resistance and the source of current.

The accompanying drawing shows the preferred embodiment of the invention, Fig. 45 1 illustrating the preferred circuit arrangement in its idle condition and Fig. 2 illustrating the system in operation.

The supply mains 1 and 2 convey current impressed thereon at the higher pressure, 50 say 100 volts, by the direct current or other generator 3 to supply incandescent lamps 4 or other load. The lamp or other resistance device 5 may, for example, have a resistance of 2000 ohms. A magnet 6, itself

of high resistance but of low resistance with 55 respect to resistance element 5 and of, say, 300 ohms, is included in series with said element in the same bridge therewith between the mains whereby the magnet is constantly energized and the lamp normally glows to 60 serve as an indicator of the working condition of the circuit.

The low voltage translating device may be of relatively low or high resistance. The device illustrated includes a magnet 7, 65 shown as of low resistance, say two ohms, normally partially included in circuit by its own armature switch 8 positioned by a spring 9 in the manner of make and break bells and buzzers to which arrangement the 70 invention is not to be limited. Supply conductors 10 and 11 respectively connect the translating device with the supply mains 1 and 2, lamp 5 being in the conductor 11. When the switch or push button 12 is closed, 75 the translating device 7 is completely connected in shunt of magnet 6. Sufficient current continues to flow through magnet 6 to maintain it energized until further instrumentalities operate. A magnet 13, whose 80 winding 14 is preferably of the high resistance of 300 ohms, is in series with the translating device 7 and together therewith in parallel with magnet 6. Magnet 13 has a normally open circuited resistance 15, say 85 of one-half ohm, which is in parallel relation with the winding 14. This resistance preferably, but not necessarily, is also a winding of magnet 13. When switch 12 is closed, winding 14 of magnet 13 is initially 90 energized, armature 16 thereupon engaging contacts 17 and 18 to close circuit through low resistance 15 to shunt the high resistance winding 14, enough current flowing through windings 14 and 15 to maintain the 95 armature 16 attracted against the force of spring 19. When the armature 16 is thus attracted a low resistance shunt is established about magnet 6 that includes the shunting resistance 20, say of three ohms, 100 the armature 16 and contact 17. The resistance of the shunt about magnet 6 that collectively includes element 20, the armature 16, and contact 17, is sufficiently high to divert sufficient current through the translating device 7, if this device is of low resistance but whether the translating device be of low resistance or high resistance, resistance 20 is

sufficiently low effectively to shunt the magnet 6. The released armature 21 of this magnet is engaged with its back contact by the spring 22. When the magnet 6 is thus shunted its released armature establishes a shunt about the high resistance lamp 5, this shunt including the current reducing resistance element 23, of say twenty ohms resistance, the armature 21 and its back contact, 10 the armature 16 of magnet 13 and the front contact 17 of this armature. The translating device 7 is now mainly fed through the low resistance element 23 included in the connection between the source of current 15 and one terminal of resistance 20 and preferably in parallel with the high resistance element 5, resistance 23 being brought into series with the translating device by the released armature 21, the resistance element 20 now functioning to prevent the undue shunting of the operating current passing through the resistance 23 to the translating device and to reduce the voltage impressed upon the translating device to the predetermined extent.

The resistance 20 is included in shunt of magnet 6 and in parallel with the translating device by armature 16 before current can flow through the resistance 23 to the translating device so that the pressure, with the assumed values hitherto given, between the supply conductors 10 and 11 can never amount to more than 15 volts, to which reduced voltage the translating device 7 is 35 subject when switch 12 is closed. With these assumed values 4.3 watts will normally flow through the magnet 6 and five amperes of current will flow to the left hand terminal of resistance 20 where the current 40 divides, a part flowing through this resistance 20 and a part through the translating device 7, these current portions being in the same ratio as the resistances 7 and 20.

The vibrating bell 7 may act so sluggishly 45 that the circuit of magnet 13 would be broken and the armature of this magnet retracted from the contacts 17 and 18, while the switch 12 is closed. I therefore make the armature 16 slow to release by providing 50 the armature end of the core of the magnet 13 with a closed copper conductor in accordance with common practice.

While I have herein shown and particularly described the preferred embodiment of 55 my invention I do not wish to be limited to the precise details of construction shown as changes may readily be made without departing from the spirit of my invention, but having thus described my invention I claim

as new and desire to secure by Letters Pat- 60 ent the following:—

1. A system of electric current distribution including a source of current; supply mains in circuit with said source of current; an electro-magnet, having an armature 65 switch, and a high resistance element included in series with this magnet in bridge of said mains; a second electro-magnet, also having an armature switch, and a translating device in series with this second magnet 70 and together therewith in parallel with the first magnet; a normally open switch for including the second magnet and the translating device in circuit; a shunting resistance element brought in parallel with the 75 translating device and in shunt of the first magnet by the armature switch of the second magnet upon the attraction thereof to de-energize the first magnet; a normally open shunt about said high resistance element and established by the armature switch of the first magnet upon the release thereof; and a current reducing winding in the connection between one terminal of the shunting 80 resistance and the source of current.

2. A system of electric current distribution including a source of current; supply mains in circuit with said source of current; an electro-magnet, having an armature 90 switch, and a high resistance element included in series with this magnet in bridge of said mains; a second electro-magnet, also having an armature switch, and a translating device in series with this second magnet 95 and together therewith in parallel with the first magnet, the second magnet having a high resistance winding and a low resistance brought into shunting relation with the high resistance winding by the armature switch of this magnet when attracted; a normally open switch for including the second magnet and the translating device in 100 circuit; a shunting resistance element brought in parallel with the translating device and in shunt of the first magnet by the 105 armature switch of the second magnet upon the attraction thereof to de-energize the first magnet; a normally open shunt about said high resistance element and established by the armature switch of the first magnet upon the release thereof; and a current reducing 110 winding in the connection between one terminal of the shunting resistance and the source of current.

In witness whereof, I hereunto subscribe my name this 5th day of February, A. D., 1920.

CHARLES A. TURNER.
